(57) **CLAIM**

The ornamental design for an indoor wall with built-in home appliances, as shown and described.

DESCRIPTION

FIG. 1 is a front perspective view of the indoor wall with built-in home appliances showing our new design;

FIG. 2 is a front view thereof;

FIG. 3 is a rear view thereof;

FIG. 4 is a left side view thereof where the right side view is a mirror image;

FIG. 5 is a top view thereof;

FIG. 6 is a bottom view thereof;

FIG. 7 is a reference view showing the use state where various modularized built-in home appliances are installed at the front bottom of the claimed design;

FIG. 8 is a reference view showing the use state that the widgets are displayed on the front center below part of the claimed design;

FIG. 9 is a reference view showing the use state that the built-in home appliances and widget are controlled by touch pad on the right of the front center below of the claimed design;

FIG. 10 is a reference view showing the use state that the front part of the claimed design can move up and down according to user's needs;

FIG. 11 is a perspective view in a condition that the front part of the claimed design has been moved up;

FIG. 12 is a front view of FIG. 11;

FIG. 13 is a rear view of FIG. 11;

FIG. 14 is a left side view thereof where the right side view is a mirror image of FIG. 11;

FIG. 15 is a top view of FIG. 11;

FIG. 16 is a bottom view of FIG. 11; and,

FIG. 17 is a reference view showing the state of use that the front center part is used as a TV.

The broken lines depict portions of the indoor wall with built-in home appliances that form no part of the claimed

(Continued)

design. The dash-dot broken lines define the boundary of the claimed design and form no part thereof.
